SAMUEL L. SAMTER, OF SAN FRANCISCO, CALIFORNIA, ASSIGNOR TO L. SAMTER & SONS, OF SAN FRANCISCO, CALIFORNIA, A CORPORATION OF CALIFORNIA

FOUR-IN-HAND TIE, METHOD OF MAKING THE SAME, AND MATERIAL USED IN THE MANUFACTURE THEREOF

Application filed March 26, 1927. Serial No. 178,518.

This invention relates to improvements in neckwear, and more particularly to that of the four-in-hand cravat type, and the piece or pattern of material from which it is cut.

In neckwear manufacture it is desirable that the patterns of the four-in-hand type, having a definite top and bottom be manufactured, such patterns, for example, being initials, fanciful designs, figures of human characters, emblems, trade or advertising designs, and the like. Neckwear containing the patterns of the above type as now manufactured and when tied presents to the eye 15 of the observer these patterns in various positions; some upside down, some on either side and others in an upright position. Such presentation of the characters to the eye of the observer when the scarf is worn 20 is the result of the arrangement of the characters on the material from which the tie is cut.

The principal object of the present invention is to overcome the above objections in 25 neckwear or cravats of the four-in-hand type and to provide a material adapted for use in cravat or tie manufacture and which contains character patterns having a definite top and bottom; to provide a material 30 which when cut to afford a tie pattern, is capable of arrangement to so present the character patterns at the opposite ends of the tie, at either side of the neckband portion, that they will all lie in an upright position when the two ends of the tie are hanging 35 vertically and will be viewable in an upright position when the tie is worn; to overcome the necessity of promiscuous arrangement on tie material of character patterns having a definite top and bottom and 40 provide a body of tie material having outline characters, each having a definite top and bottom and grouped with corresponding points facing each other on opposite sides of a dividing line extending longitudinally of the material.

With the above mentioned and other objects in view, the invention consists in the novel construction and combination of parts 45 hereinafter described, illustrated in the ac-

companying drawings and pointed out in the claims hereto appended; it being understood that various changes in the form, proportion, size and minor details of construction within the scope of the claims may be 55 resorted to without departing from the spirit or sacrificing any of the advantages of the invention.

In the drawings disclosing one embodiment of my invention—

Fig. 1 is a view in inverted plan of the full width of a piece of scarf or neckwear material illustrating the arrangement of the character outline patterns on the surface thereof, with the pattern outline of a four-in-hand cravat laid out thereon, it being understood that the material is generally cut when laid with its face downwardly disposed.

Fig. 2 is a view in plan of the pattern of 70 cravat cut from the piece, assembled and ready for folding into tubular form, and illustrating the character pattern at opposite sides of the neckband, positioned with their bottom portions disposed toward the respective ends of the cravat.

Fig. 3 is a view of a cravat ornamented with character patterns, as the same appears when worn.

In the drawings, wherein like characters 80 designate corresponding views,—1 indicates a piece of material suitable for the manufacture of cravats, and of a width from which a tie pattern may be cut on the bias. The surface of the material is ornamented 85 in any suitable manner, either during or after manufacture, by the character patterns 2, of any desired design, having a definite top and bottom.

In the present illustration, the character 90 designs for convenience in drafting, each consists in a relatively heavy block character *a* surmounted by two small block characters *b*, the latter indicating the head or top of the character and the former defining the bottom. The above illustration is explained as employed merely for simplifying the invention and rendering the making of the drawing easy; it is to be understood, however, that any suitable character 95 100

outline design, for example, a baseball, golf or tennis player, a bouquet of flowers on stems, letters or character groups necessary to lie in a certain position to form the reading thereof, and, in fact, any character outline or design which has a definite top and bottom which must be disposed in a certain position to be understood or comprehended.

Character outline designs 2 are arranged 10 preferably in relatively uniform relation throughout the area of one surface of the material, those on opposite sides of a line C—C extending longitudinally of the material, preferably at its center, although it 15 may be offset a slight distance either side of the center, having their bottoms disposed toward the opposite side edges of the material, and their tops disposed toward each other, and the dividing line disposed longitudinally of the material. The arrangement 20 of the designs is clearly illustrated in Fig. 1, in which view they are visible as viewed from the back of the material.

In cutting a tie from a piece of material 25 ornamented in the above manner, the material is preferably laid face downwardly and that portion to provide the large end of the tie 4' is cut on the bias inwardly from one side on lines 3 and 4, which lines intersect at a point 5 inwardly removed a slight distance from the opposite side of the material.

It will be observed that this piece of material which is to be used in forming the

35 large end of the tie contains, near its tapering upper end, characters which will appear up-side-down when the piece is held in vertical position, this, however, is not objectionable as the tapering upper end 6 40 assists in forming the neck-band portion of the tie, and when the tie is worn, is concealed beneath the collar. The material to provide the smaller or narrow end 7 of the tie, that portion which lies beneath the 45 larger and wider end when the tie is on the wearer, is also cut on the bias of the piece of material, its side edges converging inwardly to form a tapered end 7'. The inner tapered end 7' of the smaller end of the tie 50 forming portion 7 extends across the longitudinal character dividing line C—C in the piece of material 1 and contains character designs which will appear up-side-down when the piece is held in vertical position; this, however, is of no consequence as the 55 tapered end portion 7' of the smaller or narrower end 7 of the tie is laid adjacent to the tapered end 5 of the larger end 4' and is attached thereto by sewing the major portions 60 of the tapered ends 6' and 7' of the respective tie forming ends 4' and 7, affording the collar or neck-band portion of the tie after the same has been folded into tie forming position.

65 In making subsequent bias cuts of the

piece of tie forming material it will be observed that the ends of the respective pieces forming the large and small ends of the tie when finished are alternately laid out on the piece of material facing opposite side edges, thus for each piece which is to be cut and form the large end of two different ties there are cut from the main piece of material two pieces each to form one of the small ends of the two ties. In this manner there is no waste of material as the entire width and length thereof is used in making the ties. The material may be cut by other methods, but the above described has been found to be the most economical and by it the most satisfactory ties have been produced. While I have illustrated and described the material and its use in the making of four-in-hand ties, the same is equally as well adapted for use in the making of other types of ties.

In tying the tie, the same is slipped through the band of the collar 8, in the usual manner, and the four-in-hand knot 9, of the conventional type, is tied, in the usual manner, leaving the ends 4' and 7 depending in a vertical position, the large end 4' overlying the smaller end 7. From an examination of Fig. 3, it will be observed that the characters 2, which are visible in the knot portion have their tops all disposed in the same direction, and that the characters 2 visible in the end portions 4' and 7 have the tops of their characters all upwardly disposed.

I claim:—

1. The method of making a four-in-hand cravat, which consists in providing a fabric body ornamented with designs or characters having a defined top and bottom arranged in a defined pattern with the tops of the characters at opposite sides of a dividing line extending longitudinally through the material disposed toward said line, cutting the material on converging lines from one edge inwardly on the bias across said dividing line and falling short of intersecting the opposite edge of the material providing a tie forming piece tapering from its outer end inwardly, cutting the material on converging lines from the other edge inwardly on the bias across the said dividing line to provide a second tie forming piece tapering from its outer end inwardly, positioning the two tie forming pieces in end to end relation with certain edges in cooperative relation and with the tops of the major portions of the characters of the respective tie forming pieces disposed toward each other, and uniting the cooperating edges of the tie forming pieces.

2. The method of making a four-in-hand cravat, which consists in providing a fabric body ornamented with designs or characters having a defined top and bottom arranged in a defined pattern with the tops of the

- characters at opposite sides of a dividing line extending longitudinally through the material disposed toward said line, cutting the material on converging lines from opposite edges inwardly on the bias across said 5 dividing line providing tie forming pieces tapering from their outer ends inwardly, alternate tie forming pieces being arranged adjacent to each other with their pointed ends projecting beyond each other.
- 10 3. The method of making a four-in-hand cravat, which consists in providing a fabric body ornamented with designs or characters having a defined top and bottom arranged in a defined pattern with the tops of the 15 characters at opposite sides of a dividing line extending longitudinally through the material disposed toward said line, cutting the material on converging lines bias across the material and beyond the dividing line to provide 20 tie forming pieces each having one end terminating at the side edge of the fabric and the other end terminating at a point inwardly of the fabric between the longitudinal side edges.
- 25 In testimony whereof I have signed my name to this specification.
